UNITED STATES PATENT OFFICE.

WELI KAARLO ARMAS PALOHEIMO, OF HELSINGFORS, FINLAND.

STUMP-PULLING MECHANISM.

1,383,995.

Specification of Letters Patent. Patented July 5, 1921.

Application filed April 9, 1920. Serial No. 372,639.

To all whom it may concern:

Be it known that I, WELI KAARLO ARMAS PALOHEIMO, a citizen of the Republic of Finland, residing at Kidaelsgatan 3, Helsingfors, Finland, have invented certain new and useful Improvements in Stump - Pulling Mechanism, for which I have filed an application in Germany on Feb. 1, 1919, of which the following is a specification.

10 My invention relates to stump pulling machines and more particularly to a machine in which a crane is utilized to uproot the stumps.

Primarily, I aim to provide a simple and compact apparatus which will efficiently perform its designed functions and in which portions of the stump pulling mechanism are utilized as means for transporting the apparatus when it is in non-operative position.

20 My invention further comprises an arrangement for conveniently rendering the portions of the hoisting apparatus which are used for the transportation of the device, operative to serve as either rolling elements or as stump pulling mechanism, as desired.

The drawings accompanying this specification and forming part thereof show one embodiment of my invention.

Figure 1 shows a side elevation of my apparatus in position for transportation;

Fig. 2 shows a side elevation of my apparatus in position for pulling a tree stump; and

Fig. 3 shows an end elevation of the apparatus as shown in Fig. 2.

In the drawings a crane indicated in its entirety by 1 preferably consists of a pair 40 of diverging planks connected at their upper ends by suitable tie-bolts and at their lower ends by suitable spreader boards 2. The spreader boards together with the planks of the crane provide a suitable receptacle for containing tools and the like. A laterally shiftable axle 3 is provided at the lower end of the crane and has a pair of fly wheels 4 preferably disposed on each end thereof. A cross pin 5 transversely 45 passes through the planks at the upper end of the crane and is adapted to be utilized for attaching one end of the requisite block and tackle for lifting the crane during the stump pulling operation. A block and tackle consisting of the two blocks 6 and 7 has one of these blocks, namely the block 6 attached

to the crosspin 5. The other block 7 is secured to any convenient immovable object such as a tree by a tie-rope 8. A spring 9 of the usual construction is secured to a 60 convenient cross piece attached to the crane and serves as a locking ratchet for a windlass to be described. A pair of detachable crank handles 10 are normally attached to the ends of shaft 3 and serve as manipulating members to rotate it. A rope or chain 11 or any other suitable connecting means has one end attached to an eye-bolt provided at the upper end of the crane and its other end provided with a hook 12 adapted to engage a 70 rope or chain passing around the stump. A fender 13 is attached to the upper end of the crane and serves to prevent contact of the crane pieces with the ground and obviate consequent wear of the crane planks 75 when the apparatus is in position for transportation. Near the lower end of the crane and between the side pieces thereof, there is provided a windlass 14 of the usual construction preferably located above the axle 3 and 80 in normal stump pulling position, connected therewith by means of gears and providing the usual mechanical power advantage to the windlass. By laterally shifting the axle 3, its gear may be disengaged from the windlass gear. One end of the tackle rope 15 which passes around the blocks 6 and 7 passes around this windlass and serves to cause the blocks 6 and 7 to approach when the drum of the windlass 14 is rotated. A 90 bearing post 16 projects outwardly from the crane and has its outer end connected to the frame by a suitable bracing strut. The end of this bearing post is adapted to abut against the tree stump to be uprooted and 95 thus prevent movement of the bottom of the crane relatively to the ground.

When transporting my apparatus it is placed in the position shown in Fig. 1 and is moved from place to place on the wheels 4, 100 which as above indicated, serve as fly wheels when the apparatus is used to pull stumps. When it is desired to uproot a stump the apparatus is tilted into the position shown in Fig. 2, with the end of the member 16 105 abutting against the tree stump, and the rope 11 attached to the stump, the connecting rope 8 is then attached to any convenient immovable object such as a tree, the axle 3 shifted to such position that its gear engages the gear of the windlass and the handles 10 are manually rotated thereby causing 110

the end of the rope 15 attached to the windlass drum 14 to roll up on it and to cause the blocks 6 and 7 to approach. As the blocks 6 and 7 approach, the end of the crane 1 is rotated in a counter-clockwise direction as shown in Fig. 2 until sufficient force is exerted on the rope 11 to draw the stump out of the ground.

What I claim is:—

- 10 1. In a machine for pulling tree stumps, the combination of a beam, one end of which is adapted to be connected to a tree stump, and the other end of which is adapted to rest on the ground; and means to move 15 the end of the beam, comprising a windlass mounted on said beam.
2. In a machine for pulling tree stumps, the combination of a beam, one end of which is adapted to be connected to a tree stump, 20 and the other end of which is adapted to rest on the ground; means comprising a windlass mounted on said beam, a block and tackle to move the end of the beam connected to the tree stump, and a bearing post, rigidly secured to said beam and projecting therefrom to maintain the bottom of the beam spaced from the stump to be pulled.
- 25 3. In a machine for pulling tree stumps,

the combination of a beam, one end of which is adapted to be connected to a tree stump, 30 and means comprising a fly-wheel mounted on said beam to move the end of the beam connected to the stump, the fly-wheel serving as a wheel for transporting the machine from place to place when the latter is in 35 transportable position.

4. In a machine for pulling tree stumps, the combination of a beam, one end of which is adapted to be connected to a tree stump, and means comprising an axle having fly-wheels adapted to roll on the ground when the machine is transported from place to place, said axle carrying a gear, and a windlass drum carrying a gear to move the end 45 of the beam connected to the stump, with means for disconnecting said gears when the windlass is out of use, to permit the free turning of the axle and fly-wheels.

In witness whereof, I have hereunto signed my name in the presence of two subscribing witnesses.

WELI KAARLO ARMAS PALOHEIMO.

Witnesses:

RAGNAR KAJANDER,
F. KOTOTER.
